UNITED STATES PATENT OFFICE

112,042

DESIGN FOR A LOBSTER FORK

Ernst Johansson, Jr., Hoboken, N. J.

Application August 24, 1938, Serial No. 79,552

Term of patent 14 years

To all whom it may concern:

Be it known that I, Ernst Johansson, Jr., a citizen of the United States of America, residing at Hoboken, county of Hudson, and State of New Jersey, have invented a new, original, and ornamental Design for a Lobster Fork, of which the following is a specification, reference being had to the accompanying drawing, forming part thereof wherein:

Figure 1 is a plan view of a lobster fork, showing my new design.

Figure 2 is an edge view.

I claim:—

The ornamental design for a lobster fork, as shown.

ERNST JOHANSSON, JR.
